UNITED STATES PATENT OFFICE.

ALFRED A. POPE, OF CLEVELAND, OHIO.

DESIGN FOR A VEHICLE-STEP.

SPECIFICATION forming part of Design No. 22,404, dated May 2, 1892.

Application filed October 25, 1892. Serial No. 449,987. Term of patent 14 years.

To all whom it may concern:

Be it known that I, ALFRED A. POPE, of Cleveland, in the county of Cuyahoga and State of Ohio, have invented a new and original Design for Vehicle-Steps, of which the following is a full, clear, and exact description.

The accompanying drawing shows in perspective view a vehicle step embodying my design.

The design consists in a vehicle step and stem, said stem having at the juncture the form substantially as shown in the accompanying drawing, and herein described, and said stem being forked at its lower extremity, the forked branches thereof extending forwardly, diverging from each other to the step pad at or near the rear corners of the latter.

In the drawing, 2 represents the step pad, and 3 the upright stem, having at its lower end forked branches which extend forwardly and are connected to the pad at or near the rear corners.

I claim—

The design for vehicle steps substantially as herein described and shown.

In testimony whereof I have hereunto set my hand this 22d day of October, A. D. 1892.

ALFRED A. POPE.
